PERFORATOR

Jacob Sigurt Andersen, Pasadena, and Warren C.
Putnam, Los Angeles, Calif.

Application September 4, 1937, Serial No. 162,554

17 Claims. (Cl. 101—19)

This invention relates to perforators of the class having a plurality of individual lever-operating perforating elements selectively movable into alignment for simultaneously forming a series of perforated indicia in paper or other easily pierceable material.

While marking for identification purposes may be effected in many ways, where it is desired to mark a series of papers, coupons, pages of a book, or like subject-matter with the same indicia, it is best effected by means of a perforator which punches a series of minute holes through the matter to be marked in the desired configuration. Advantages common to all of such conventional perforating devices are that the identifying perforations may be made on most any part of the matter to be marked, e. g., over other printed matter, without weakening the legibility of either printed or punched characters, thus obviating much of the usual care required in the disposition of printed indicia with respect to other printed matters; that the same indicia may be punched through a series of separably usable pages with a minimum of effort and time; and that numerous printing accessories necessary to many other conventional marking means and methods are entirely dispensed with.

It is a general object of the present invention to provide a device embodying the above noted advantages, characterized by more expeditious operation and wider scope of utility.

A more specific object is the provision of a perforator structure having a plurality of perforating characters selectively movable into operative position for individual or simultaneous use whereby one or a series of perforated characters may be punched during a single stroke of a manually actuated lever.

Another object is to provide a series of perforating elements carrying wheels revolvable to bring the perforating elements into alignment with supporting means for matter to be perforated by means of a lever, in combination with means to increase rotary velocity of said wheels with respect to the lever.

Another object is to provide novel means for manually moving a supporting table against a series of perforating elements including a toggle joint connection to enable the attainment of maximum pressure between the table and the perforating elements.

Another object is the provision of the structural combination of means to drive matter to be perforated on a plurality of pins to form a perforated configuration, and a stripper mechanism

for removing said matter from the pins at the conclusion of the perforating operation, the manual actuation of both of said perforating and stripping mechanism being augmented by the tension of a spring extended by preliminary movement of the means for actuating said stripper and pin driving mechanism.

Another object is to provide a gage for fixing the extent matter to be perforated may be admitted into a recess under the perforating pins, said gage having means employed therewith to secure it in any adjusted position, whereby matter successively marked will be perforated at uniform distances from its margin.

Another object is to provide, in a device of the character above designated having a supporting table for matter to be perforated and a plurality of perforating pins, of means for assuring alignment of the perforating elements carried individually by revolvable wheels for use simultaneously, comprising a latching device for the means adapted normally to compel the movement of the supporting means and pins in performing their perforating operation, said latching device being actuated by the misalignment of any of the perforating elements with respect to the supporting table.

Another object is to provide a perforating element comprising a series of pins mounted in a laminated back, combining strength in use with ease of assembly and economy of manufacture.

Other objects and corresponding advantages such as simple, positive operation, efficient utilization of parts, replacement of worn parts, and durability, will be apparent to those of skill in the art from an examination of the following description read in the light of the accompanying drawings, in which:

Figs. 1 and 2 are side and front elevations, respectively, of my invention;

Fig. 3 is a sectional view through a side of the device taken on lines 3—3 of Fig. 2, illustrating certain parts in elevation;

Figs. 4, 5, 6, and 7 are sectional views taken on correspondingly numbered lines of Fig. 3;

Fig. 8 is a sectional view on line 8—8 of Fig. 3, illustrating in elevation the safety mechanism to prevent operation of the device when not properly set;

Fig. 9 is a broken sectional view of a segment of one of the wheels illustrating particularly a perforating element carried thereby;

Fig. 10 is a plan view of one of the perforating elements;

Fig. 11 is a sectional view taken on lines 11—11 of Fig. 3;

Fig. 12 is a plan view of matter perforated by the present invention;

5 Fig. 13 is an enlarged view of one of the perforating pins.

Referring to the drawings in detail, the numerals of which indicate similar parts throughout the several views, 13 designates a base on 10 which are mounted at opposite ends thereof, by means of bolts or the like, a pair of horizontal brace bars 14, parallel to each other. Side supporting walls 15 and 16 are bolted on opposite ends of bars 14, through which the threaded ends 15 of the bars extend, said walls being supported by base 13. A portion of the forward edge of each of said supporting walls is reentrant to form the ends of a perforating-recess 17. A curved back cover 18 (Fig. 3) is secured at its 20 bottom edge to the rear bar 14 to inclose the back of the perforator between walls 15 and 16. The upper end of back cover 18 is secured to a pair of blocks 20 mounted on a transverse rod 19 having its opposite ends mounted in walls 25 15 and 16. A slotted index plate 21 provides an extension of the cover 18 being secured by screws or the like to blocks 20 at its upper end and extending to the front of the perforator for attachment to blocks 22 carried on a transverse rod 30 23, which in turn is mounted in holes of the opposed walls 15 and 16. An extension plate 24 is similarly secured to blocks 22 and defines the upper edge of the perforating-recess. An oblique front plate 25 is secured to the foremost 35 bar 14 and extends upwardly into the recess 17. 26 indicates a reinforcement plate (Figs. 4 and 5) bolted rigidly to each supporting wall adjacent the perforating recess.

A horizontal arbor 27 is journalled at its opposite ends in centrally disposed bearings of walls 40 15 and 16. On arbor 27 a plurality of wheels 28 are rotatably supported, carrying the perforating elements later referred to in detail. The wheels 28 are individually revolvable on arbor 45 27 and being separably operable in use, it will be apparent that any number of such wheels may be utilized, depending upon the number of individual perforated configurations which the device is adapted to make simultaneously.

50 A series of flat shoes 29 (Fig. 9) are formed equi-spaced apart on the periphery of each wheel, the outer face of each shoe being disposed at right angles to a radius of wheel 28 through its center. Perforating elements, generally designated at 30 are mounted on all but one or any 55 group of said shoes, each element comprising a laminated back 31. A series of holes are punched transversely in each lamination 32, separately, of the back 31 in the form of the desired configuration which the element is to perforate, as for example, a letter or a numeral. Laminations 32 are then assembled one on the other with the punched holes aligned and a pointed pin 33 is driven through each of the series of 60 aligned holes to frictionally retain the laminations together, and hold the pins rigidly parallel with respect to each other. The laminations and pins may be soldered or otherwise secured immovably together. The backs 31 of the elements 30 are secured to shoes 29 respectively, by means of screws or the like, with the pointed ends of the pins 33 extending outwardly from the respective wheels.

70 Each wheel 28 may accordingly be rotated to bring any of the perforating elements carried

thereby to a position adjacent the perforating recess and in vertical alignment with the arbor 27 by means of a control lever 34 (Fig. 3), pivoted at its inner end on arbor 27 adjacent the wheel it is adapted to control and extending 5 radially outward through an aligned slot 35 in plate 21. On the outer end of each control lever 34, a split handle 36 is mounted by means later referred to. A spur gear 37, located parallel to and between each control lever 34 10 and the wheel it is adapted to actuate, is pivoted on the lever 34 intermediate the ends thereof so as to mesh with a spur gear 38 concentrically and rigidly mounted to the adjacent wheel. In the vertical plane of each set of spur gears 37 and 15 38 under and adjacent the plate 21, a ring gear segment 39 having inwardly-extending gear teeth 40, is provided to mesh with the side of spur gear 37 opposite to the point thereon of the mesh of said gear with spur gear 38. The ends of ring gear segment are mounted on rods 19 and 23, adjacent ends of respective segments, being separated by blocks 20 and 22 and suitable spacers (not shown).

To prevent the teeth of spur gear 37 from 25 slipping out of mesh with the teeth 40 of the gear ring segment, the outer end of each control lever is longitudinally slotted as at 42. A member 43 is retained in each of slots 42 between the bifurcations 44 (Fig. 4) of the split handle 30 36. The handle, member 43 and control lever are held in position by means of a screw or the like extending through the handle and member. The lower inner end of member 43 is bent at right angles across the gear ring segment between the 35 same and plate 21, and thence downwardly on the side of the segment 39 opposite to that on which the lever is disposed, whereby each gear segment is held between, respectively, a lever 34 and an adjacent member 43 to prevent its lateral 40 displacement with respect to the teeth of spur gear 37. Wheels 28 are thus geared with the handles 36, and with the latter against the upper end of slots 35, the unoccupied shoes 29 will be at the bottom of the wheels, in vertical alignment with the arbor 27 and adjacent the perforating-recess 17. The position of handles 36 with respect to indicia of an index carried on the face of plate 21 is correlated with the position of the perforating elements with respect to the 50 perforating-recess, as will be obvious to those of skill in the art. The ends of the slots 35 limit movement of the control levers and correspondingly the opposite ends of the oscillatory movement of the wheels 28.

55 A pair of inclosing outside plates 46, supported on base 13 cover the walls 15 and 16 (Fig. 6). Arbor 27 extends through plates 46 and is threaded on its ends for nuts 47 which hold the plates 46, supporting walls 15 and 16, and mechanism 60 therebetween, including wheels 28, gears 38 and 39, and control levers 34 in the above described operable association.

Below the wheels 28, a vertically movable table 48 forming the bottom of recess 17 is supported, 65 by means hereinafter described in detail, for the support of matter to be perforated, as for example, a book of coupons 49 (Fig. 12). Table 48 comprises a horizontal channel member 50, in vertical alignment with arbor 27. A supporting 70 plate 51 having a downwardly extending flange 52 bolted or otherwise secured to the side of channel member 50 forms a part of table 48 between the upper edge of channel member 50 and the upper edge of the front plate 25. A 75

wooden block 53 is slidable between the side walls 54 of member 50 and flush with the upper edges of said walls providing a cushion for the pins 33 of the perforating elements 30 when the table is moved against the pins as hereinafter described. The side walls 54 of channel member 50 are longitudinally grooved at 55 as are the adjacent walls of block 53. A U-shaped wire 56 having its ends extending into the adjacently aligned grooves of the walls 54 and block 53 keys the block in member 50. The ends of the member 50 are extended into closely fitting vertical recesses 57 formed in the supporting walls 15 and 16 and in reinforcement plate 26, which 10 guide the table 48 in its vertical movement. The bottoms of the recesses 57 limit the downward movement of the table.

The table is raised from the bottom of recesses 57 by mechanism about to be described, which 20 is actuated manually by means of a handle 58 keyed to the outer end of a shaft 59 extending through supporting wall 15 and the adjacent inclosing wall 46. The opposite end of shaft 59 extends through and is journalled in supporting 25 wall 16. Shaft 59 is connected to a pair of pins 60 journalled in projections 61 integrally formed on the underside of channel member 50 by means of a toggle joint mechanism which consists of a bifurcated arm 62 secured rigidly on shaft 59 30 intermediate walls 15 and 16, carrying a pivot 63 parallel to shaft 59. A connecting arm 64 having one end journalled on pivot 63 has its opposite end pivoted to one end of a toggle 65. The opposite end of toggle 65 is pivoted on a shaft 66 35 journalled in supporting walls 15 and 16. A pair of toggles 67 are pivoted to toggle 65 intermediate the ends thereof and extend across a line through the points of pivot of the ends of toggle 65, being pivotally connected to pins 60, journalled in table 48.

40 It will be apparent that upon the partial rotation of shaft 59 effected by drawing the handle 58 downwardly that the connecting arm 64 will be moved rearwardly due to the eccentric position of the pivot 63 with respect to the shaft 59. 45 This movement of arm 64 swings toggle 65 on its pivot on rod shaft 66, raising and moving rearwardly the point of pivot of the toggles 67 thereon. As the table 48 is restrained from lateral movement by the portions of the supporting 50 walls 15 and 16 forming the recesses 57, the elevation of toggles 67 causes upward movement of the table urging the paper on the table, onto pins 33 of the perforating elements 30 to form the perforations 68 in the matter 49.

55 To assist this operation, and particularly to counteract the increasing pressure of the handle 58 necessary to drive the paper to be perforated onto the perforating pins, a radial arm 69 (Fig. 5) is keyed to the end of shaft 59 which 60 extends through supporting wall 16. A coil spring 70 (Fig. 8) having one end pivoted to supporting wall 16 as at 71 directly above shaft 59 is attached to the free end of the radial arm which, with the table in its lowermost position, 65 extends forward slightly below the horizontal. As the shaft 59 is turned upon movement of handle 58, the spring 70 will be extended until dead center is reached, i. e., with the axes of the spring and arm 69 parallel, which will occur 70 after less than one-half of the approximately 90° of movement of the handle 58. The counteraction of spring 70 will, during the remainder of the stroke of the handle, accordingly be effective in urging the elevation of the table and perforation

of the material operated upon. The spring 70 will similarly assist in affecting a complete return of the handle to its original position, and accordingly facilitate the operation of the stripper mechanism about to be described. 5

The stripper for removing the perforated material from the pins 33 comprises a hub 72 mounted rigidly on a transverse tube 73 journalled in opposed supporting walls 15 and 16 in substantially horizontal alignment with the perforating recess 17. Secured integrally with the hub and extending into the recess 17 in vertical alignment, respectively, with the areas between different pairs of wheels 28, are a series of spaced parallel stripper tongues 74. The forward ends 10 of tongues 74 are turned upwardly to guide the material to be perforated between the lower edges of the tongues and the table 48. A return bar 75 is secured rigidly to the bottom of the hub 72, by any means well known in the art, with its 20 free end extending under the channel member 50 between projections 61. A spring finger 76 secured in tube 73 on the outside of the supporting wall 16 is sprung under a pin 77 secured to said supporting wall, said finger being bent in a 25 counterclockwise direction from the point of its attachment to the tube 73 whereby the finger will urge like counterclockwise movement of the hub 72 normally to retain the bar 75 against the underside of channel member 50 and maintain 30 maximum spacing of the table 48 and stripper tongues 74. When the table is raised, the material to be perforated will push the tongues 74 between the wheels 28 permitting the pins 33 to 35 perform their perforating function. Upon return of the table to its lowermost position, the channel member will bear against the free end of bar 75 causing the hub 72 to rotate and the stripper tongues 74 to follow the table, thus removing the 40 perforating material from pins 33.

78 indicates a variable gage limiting the depth of the perforating recess 17 to provide an abutment against which material to be successively inserted into recess 17 for perforation may be held, and thereby insure its uniform perforation 45 with respect to the margins thereof. Gage 78 is carried in recess 17 to the rear of channel member 50 and below stripper tongues 74 by a rod 79 secured to its middle at right angles thereto. Rod 79 extends slidably through a hole 50 80 bored through hub 72 substantially parallel to bar 75. The hole 80 through the hub intersects the bore of tube 73. A coil spring 81, having one end secured to the underside of bar 75 and its opposite end connected by means of a 55 downwardly projecting finger 82 secured to the rearward end of rod 79, urges, by its tendency to compress, the rods 79 and gage 78 to a foremost position. The gage 78 may be held in any adjusted position by means of a retaining pin 83 60 (Fig. 6) adapted to be threaded into the bore of tube 73 for the frictional engagement of rod 79 at the point thereon where said rod intersects the bore of the tube. A knurled handle 84 on the outside of the pin facilitates manipulation 65 of the pin from the outside of the inclosure plate 46 through which the tube extends.

To assure perfect alignment of the perforating elements 30 carried by wheels 28 upon manipulation of handle 36, a safety device is provided 70 to prevent movement of handles 36 and elevation of the table except when such alignment is effected. A transverse rod 85 has its opposite ends carried rigidly in supporting walls 15 and 16 between wheels 28 and the upper end of rear cover 75

18. On rod 85 are pivoted a series of restraining arms 86. Arms 86 extend rearwardly and downwardly to a position with their free ends normally overhanging a stop bar 87 mounted at the rearward side of shaft 59 to the arm 62 and parallel to said shaft. The contact of bar 87 with the free ends of the restraining arms 86 will accordingly prevent rotation of the shaft by which the perforating operation is motivated. A pivot rod 88 is journaled in the supporting walls 15 and 16 above the lower ends of arms 86. A control plate 89 is secured to pivot rod 88 and extends obliquely upward, being normally supported substantially parallel to the arms 86 by means about 15 to be described. A right angle extension 90 of the control plate 89 is formed with a plurality of parallel slots 91 (Figs. 6 and 8) in which individually the arms 86 are maintained against lateral displacement. A plurality of adjusted screws 92 extend loosely through, respectively, each of a series of holes in the upper end of plate 89 aligned respectively with arms 86. Each screw 92 is threaded tightly into the bore of a coil spring 93 which springs have their opposite ends attached respectively to the arms 86. The tension of springs 93 on the arms tends to draw the lower ends of the arms free from engagement with the bar 87, permitting the shaft 59 to be turned without restraint. A cam 94 is mounted 20 rigidly on shaft 59 adjacent supporting wall 16 on which a follower-lever 95 rides having its opposite end pivoted on rod 88. A portion of the follower-lever 95 is extended above rod 88 for the support of a transverse pin 96 adapted 25 to bear against the control plate 89 intermediate rod 88 and the attachment of springs 93 thereto, whereby rotation of the shaft 59 and cam 94 causes the lower end of the cam follower to be moved laterally from the axis of the shaft, utilizing the rod 88 as a fulcrum to tilt the plate 89 rearwardly on the axis of rod 88, resulting in the extension of springs 93, so as to increase their tension as the shaft 59 is moved downwardly and thereby increase the tendency of the springs to 30 draw the arms rearwardly on rod 85, for a purpose hereinafter more in detail described.

The shoes 26 heretofore referred to, forming the support for the perforating elements 30, are slightly wider than the thickness of wheels 28. 50 A rider 97 secured to each arm 86 by means of a rigid laterally extending member 98 engages the underside of the overhang of shoes 29 on each wheel 28 and holds the respective arms 86 forward to a position contacting the bar 87 to 55 block operative movement of shaft 59 and handle 58. The space between shoes 29 on each wheel 28 provides notches 99 into which the riders 97 drop, when aligned therewith, in response to the tension on the arms 86 of respective springs 60 93 thereby moving the lower end of the arms 86 rearwardly and out of the arcuate course of the bar 87 upon movement of shaft 59. The riders 97 contact each notch 99 successively as the perforating elements 30 are moved into vertical alignment with the wooden block 53 of the channel member 50. When the wheel-operating handles 36 are moved to the desired index numeral or letter on the face of plate 21, and riders 65 97 are drawn into respective notches 99 between certain of the shoes 29, depending upon the rotational disposition of the wheels 28, the shaft 59 may be turned manually by means of the handle 58, causing the cam 94 carried thereby to tilt plate 89 and increase the tension of springs 93 as above described. Thus, the tension of the

springs 93 will resiliently hold the riders 97 in the centers of notches 99 to resist tendency of the wheels 28 to become misaligned either before or during perforation of the matter acted upon.

It will be apparent, however, that to turn 5 wheels 28 the riders must of necessity leave the notches 99, i. e., in order to ride on shoes 29, which operation, as above noted, draws the arms 86 forward, bringing the lower ends thereof into alignment with the line of movement of stop bar 10 87. Conversely, the table-elevating movement 15 of shaft 59, when the riders are centrally located in notches 99, causes the bar 87 to move into alignment with the lower ends of arms 86 to prevent their inward swing, i. e., toward the 20 shaft, incident to the movement of the riders from notches 99, thereby locking wheels 28 and the perforating elements 30 in aligned position throughout the perforating and return strokes of handle 58. 25

While we have described but one embodiment of our invention, it will be apparent that many of the structural features of our invention may be omitted or substituted by conventional expedients, but that such separable features are both 25 individually and combinatively part of the present invention; and further, that numerous changes in shape, number, size, and proportion of the various parts may be made herein—all without departing from the spirit of our invention as defined in the appended claims. 30

What we claim and desire to secure by Letters Patent is:

1. In a perforator, a wheel a plurality of perforating elements each comprising a series of laminations, and a series of perforating pins extending through individual holes in said laminations to retain said laminations and pins rigid with respect to each other, and means to clamp the laminations of each of said perforating elements together and said perforating elements in spaced relation on the periphery of said wheel with said pins radially disposed with respect to said wheel with their lower ends in abutting contact with said wheel whereby said wheel resists longitudinal movement of the pins toward the center of the wheel. 35

2. In a perforator, a case having a slotted index plate comprising one wall thereof, a plurality of wheels journaled within said case, perforating elements carried on each of said wheels, a gear carried concentrically on each of said wheels, a series of levers pivoted on the axes of said wheels and adjacent to respective wheels, a ring gear segment secured in said case adjacent said index plate, a spur gear pivoted on each of said levers, and means to retain said spur gear in mesh with said first-named gear and said ring gear segment. 50

3. In a perforator, a case, a perforating element carried in said case, vertically movable means for the support of matter to be perforated adjacent said perforating element, means to raise and lower said first-mentioned means and thereby urge matter to be perforated on said perforating element, and a stripper having an arm connected thereto engaging said vertically movable means, said arm being actuated by movement of said first-mentioned means to lower said stripper with respect to said perforating element and thereby remove matter perforated from said perforating element. 60

4. In a perforator, a case, a perforating element supported in said case, a table for the support of matter to be perforated movably carried 65

in said case normally spaced from said perforating element, means to move said perforating element and said table together and apart, a stripper tongue, means to pivotally support one end of said tongue in said case, said tongue having its free end terminating above said table, and a lever connected to said stripper tongue extending beneath said table to move said tongue in the direction of movement of said table with respect to said perforating element upon separation of said perforating element and said table.

5. In a perforator, a case, a pair of wheels, a perforating element carried on the periphery of each of said wheels, a table for the support of matter to be perforated, means for moving said table against said wheels including a rotatable shaft, a pair of levers pivoted in said case adapted to gravitate against said shaft to lock the same against rotation, means on said wheels to hold respective levers in a position blocking rotation of said shaft, means to draw said levers free of said blocking engagement with said shaft, and means on said wheels to release said lever from locking said shaft, said last-named means being operable by alignment of any of said perforating elements with said table and with each other.

6. A perforator of the character described in claim 5 in combination with means to retain perforating elements aligned with said table and with each other in such aligned relationship during movement of said table.

7. In a perforator, a case having a curved index plate comprising one wall thereof, a plurality of wheels rotatably mounted in said case, a plurality of shoes on the periphery of each of said wheels spaced from each other, a perforating element mounted on each of said shoes, said shoes being wider than the thickness of said wheels, a table for the support of matter to be perforated, a lever connected to each of said wheels extending through said index plate to cause rotation of said wheels, means to vertically move said table and wheels until they are together, and means actuated by relative vertical movement of said table and wheels to engage between said shoes to releasably hold said wheels in a position with any of the perforating elements carried thereby in alignment for perforating.

50. 8. In a perforator, a case having a slotted index plate, a plurality of wheels, a plurality of shoes wider than the thickness of said wheels carried by each of said wheels, a perforating element comprising a series of pins mounted on each 55 of said shoes, a ring gear segment secured to the underside of said index plate, a plurality of levers pivoted on the axes of said wheels for control of each wheel individually, gearing mechanism connecting said wheels to said levers through 60 said ring gear segment, a table for the support of matter to be perforated movable against said wheels, a shaft journaled in said case, means to connect said shaft with said table to cause reciprocal movement of said table by rotative 65 movement of said shaft, a stop bar carried on said shaft, a series of blocking arms pivoted in said case at one of their ends and having their free ends movable to engage said stop bar to resist movement of said shaft, resilient means to 70 move said blocking arms from engagement with said stop bar, and a rider connected to each of said blocking arms to engage the underside of the overhang of said shoes on each of said wheels to retain said blocking arms in engagement with 75 said shaft, said rider being movable to positions

between said shoes to release said arms to the tension of said resilient means.

9. In a perforator, a plurality of perforating elements, means to align two of said perforating elements with respect to each other, means to urge matter to be perforated simultaneously on said aligned perforating elements, and means actuated by movement of said last-named means to remove material perforated from said aligned perforating elements.

10. In a perforator, a plurality of perforating elements, means to align two of said perforating elements with respect to each other, drive means to urge matter to be perforated simultaneously on said aligned perforating elements, means to block actuation of said last-named means comprising a pair of arms connected to each of said aligned perforating elements respectively, resilient means to move said arms from blocking engagement with said drive means, and means to increase tension of said resilient means.

11. In a perforator, a case, a perforating element supported in said case, a table for the support of matter to be perforated movably carried in said case normally spaced from said perforating element, means to move said perforating element and said table toward each other and apart, a stripper tongue, means to pivotally support one end of said tongue in said case, said tongue extending above said table, a lever connected to said stripper tongue extending beneath said table to move said tongue in the direction of movement of said table with respect to said perforating element upon separation of said perforating element and said table, and a gage connected to said stripper tongue so as to move vertically therewith but movable horizontally in a plane between said stripper tongue and said table.

12. In a perforator, a case, a transverse shaft in said case, a perforating wheel mounted on said shaft having a plurality of perforating elements on its periphery, a gear wheel secured to said perforating wheel, a lever having one end thereof mounted on said shaft and its opposite end extending through said case, an internal gear wheel segment secured to the inside of said case in the vertical plane in which said gear is disposed, a spur gear pivoted on said lever between said gear and said internal ring gear segment so as to mesh therewith and thereby enable rotation of said perforating wheel by movement of the end of said lever protruding from said casing.

13. In a perforator, a case, a transverse shaft in said case, a perforating wheel mounted on said shaft having a plurality of perforating elements on its periphery, a gear wheel secured to said perforating wheel, a lever having one end thereof mounted on said shaft and its opposite end extending through said case, an internal gear wheel segment secured to the inside of said case in the vertical plane in which said gear is disposed, a spur gear pivoted on said lever between said gear and said internal ring gear segment so as to mesh therewith and thereby enable rotation of said perforating wheel by movement of the end of said lever protruding from said casing, and means connected to the outer end of said lever to hold said ring gear segment and spur gear in mesh.

14. In a perforator, a case, a perforating element in said case, a movable table for the support of matter to be perforated below said perforating element, means to raise said table to move matter to be perforated carried by said table on said per-

- forating element, said means comprising a rotatable shaft journalled in said case, a connecting rod having one of its ends pivoted eccentrically on said shaft, a second shaft parallel to said first shaft journalled in said case below and in vertical alignment with said table, a toggle mounted on said second shaft and extending upward to the side thereof opposite to the side of said second shaft to which said first-named shaft is disposed, said connecting rod being pivotally connected to said toggle at a point thereon above said second shaft, a second toggle pivoted to, respectively, said first-named toggle intermediate its ends and to the underside of said table, a bar secured to and extending radially from said first-named shaft, a spring secured at one end to said case and at its opposite end to said bar, whereby rotation of said first-named shaft causes elevation of said table and simultaneously therewith the successive increase and decrease in tension of said spring.
15. In a perforator, a case, a table for the support of matter to be perforated, a perforating wheel journalled in said case in vertical alignment with said table, a series of perforating elements carried on the periphery of said wheel and thereby movable into alignment with said table and the axis of said wheel, a shaft journalled in said case, means actuated by rotation of said shaft to move said table and perforating element aligned therewith until they are together, locking means carried by said shaft, a member pivoted in said case adapted to gravitate against said locking means to block rotation of said shaft, 30 said member having means connected thereto to engage said wheel to prevent rotation of the same, resilient means to urge said member into locking engagement with said perforating wheel and from locking engagement with said shaft, 35

and means to increase the tension of said resilient means upon rotation of said shaft.

16. In a perforator, a case, a table for the support of matter to be perforated, a perforating wheel journalled in said case in vertical alignment with said table, a series of perforating elements carried on the periphery of said wheel and thereby movable into alignment with said table and the axis of said wheel, a shaft journalled in said case, means actuated by rotation of said shaft to move said table and perforating element aligned therewith until they are together, locking means carried by said shaft, a member pivoted in said case adapted to gravitate against said locking means to block rotation of said shaft, 10 said member having means connected thereto to engage said wheel to prevent rotation of the same, resilient means to urge said member into locking engagement with said perforating wheel and from locking engagement with said shaft, 15 and means on said perforating wheel to counteract the tension of said spring and urge said member into locking engagement with said locking means to lock said shaft against rotation.

17. In a perforator, a base, a perforating element carried by said base, a table adapted to support the matter to be perforated thereon adjacent said perforating element, means to raise said table toward said perforating element comprising a rod and a lever mounted on said rod, 25 a handle to turn said rod axially in both directions and thereby reciprocably swing said lever, and a spring connected to said lever to alternately urge said lever in each direction during portions of the respective reciprocating strokes 30 of the lever.
